CLOCK

Gordon Florian, Bridgeport, Conn., assignor to Sunbeam Corporation, Chicago, Ill., a corporation of Illinois

Application March 25, 1957, Serial No. 45,428

Term of patent 14 years

(Cl. D42—7)

Fig. 1.

Fig. 3.

Fig. 1 is a front perspective view of a clock embodying my new design;

Fig. 2 is a side elevational view of the clock shown in Fig. 1; and

Fig. 3 is a top view of the clock shown in Fig. 1 with a portion of the crystal cut away to show the dial.

The opposite side view of the clock is the same in appearance as the side shown in Fig. 2 and the back thereof is substantially plain.

I claim:

The ornamental design for a clock, as shown and described.
